INCREASING CONTRAST OF THE IMAGE INTENSIFIER

Martin Rome, Elmira Heights, N. Y., assignor to Westinghouse Electric Corporation, East Pittsburgh, Pa., a corporation of Pennsylvania

Application April 19, 1954, Serial No. 424,073

8 Claims. (Cl. 313—65)

My invention relates to image reproducing tubes such as those having a fluorescent input screen on which an X-ray image is projected and an output screen on which appears a light image which is a replica thereof. A tube of this type is described in Mason and Coltman U. S. Patent 2,523,132, issued September 19, 1950, and my invention will be illustrated as applied to such a tube although it has numerous other fields of application, and may be used to improve and regulate the contrasts between different portions of the output image of any reproducing tube which, like the Mason and Coltman device, embodies an electron image producing means as an agency in its operation.

One object of my invention is accordingly to provide an improved type of image reproducing tube.

Another object is to provide means for regulating and improving the contrast between different portions of the output image in an image reproducing tube.

Another object is to provide a device in which an image embodied in radiation of one type is transformed into an image in radiation of another type with means for regulating and improving the contrasts, or gamma, of different portions of the image.

Still another object is to provide an improved type of tube for transforming X-ray images into visible replicas thereof.

Other objects of my invention will become apparent upon reading the following description taken in connection with the drawings in which:

Figure 1 is a schematic view partly in cross-section of an image intensifier tube of the general type described in the above-mentioned Mason and Coltman patent;

Fig. 2 is a schematic cross-sectional view of a portion of the input screen embodying my invention for use in the Fig. 1 tube; and

Fig. 3 is a graphical plot employed in explaining my invention.

Referring to the drawings in detail, the image intensifier tube comprises a vacuum tight container 1 which may be of glass provided with an input-screen 2 consisting of a glass-plate 3 of general watch-glass form having on its convex surface a layer 4 of zinc sulphide or other fluorescent material. The concave surface of the plate 3 is coated with a transparent conductive coating 5 such as tin oxide, and the latter is faced with a layer 6 of some photoconductive material such as selenium, arsenic trisulphide, antimony trisulphide, or cadmium sulphide. The concave face of the layer 6 is coated with a layer 7 of cesiated antimony or other suitable photoelectric emitter.

At the opposite end of container 1 is an output screen 8 which may comprise a glass plate 9 coated with a layer 11 of an electron-phosphor sandwiched between glass plate 9 and a layer 12 of aluminum thin enough to be pervious to electrons made to bombard its surface in the manner about to be described. An electron lens system 13 envelopes the space between input screen 2 and output screen 8.

In operation of this image tube an X-ray image is pro-

2

jected onto the fluorescent layer 4 where it generates light which passes through glass plate 3, conductive coating 5 and photoconductive coating 6 to generate at the free surface of photoelectron emissive coating 7 an electron image 5 which is a replica in space-distribution of the X-ray field incident on layer 4. An electron-lens system 13 of any suitable type energized by source 14 which connects layers 5 and 12 focuses this electron image into incidence on the layer 11 through metal layer 12, and generates in layer 10 11 a light image which is a replica (except as pointed out below), at reduced scale, of the original X-ray image. The electron image, moving from the inside face of screen 2 into incidence upon screen 8 constitutes an electric current which cannot flow, except transiently, if a 15 complete electric circuit for its flow does not exist; and hence current must flow from front to back face from photoelectrically-emissive layer 7 to conductive layer 5 through the photoconductive layer 6. The number of electrons which can flow, as part of the electron image, 20 from a point on the concave face of layer 7 thus depends on the resistance of the portion of the photoconductive layer which underlies it. The resistance of the photoconductive layer 6, point-by-point over its area, is determined by the intensity of the light projected through it 25 by the light-image generated on the fluorescent layer 4. Thus, at a point where this light image is bright, the resistance of the photoconductive layer 6 is low, and this permits a large number of photoelectrons to be emitted per second from the photoelectrically emissive layer 7 at that point on the screen. On the other hand, at a point where the X-ray image is of low intensity, the photoconductive layer 6 is of high resistance and this permits only a relatively few electrons to be emitted per second from the layer 7 at that point of the image. In short, the 30 photoconductive layer 6 may be considered to embody a conductivity-image corresponding in distribution over the screen face to the distribution of the X-ray image, and this conductivity image modifies and accentuates the 35 contrasts in the electron image which is projected onto the output screen 8. Thus bright areas on the X-ray image are made relatively prominent in the image on output screen 8, while dark areas on input screen 2 are relatively dark on the output screen. The changes in resistivity of the photoconductive layer 45 6 are in general not strictly proportional to changes of intensity in the X-ray field but are likely to be large where the X-ray field is weak and smaller where the X-ray field is intense. The exact relationship of percentage change in resistivity in photoconductive layer 6 to percentage change in X-ray intensity depends of course on the particular material constituting layer 6. Moreover, the resistance met by the electric current at a given point in passing through layer 6 is only a part of the total resistance in the complete circuit constituting its path 50 through conductive coating 5, coating 6, coating 7, the space-path between coating 7 and output screen 8, and the external circuit leading back to conductive coating 5, and the changes in the electron-current generating light on output-screen 8 are dependent on the percentage change in resistance of this entire path. Thus, the relative magnitude of resistance in layer 6 to these other resistances acts, in conjunction with other factors such as tube 55 geometry, voltage and light intensity, to determine the ratio of the change in output light to a change in X-ray field intensity at any point, and by proportioning the relative magnitudes of photoconductive resistance to other path resistances in ways evident to those skilled in the art the change of output light per unit change in X-ray intensity may be varied at will over a wide range. Thus 60 in Fig. 3 a curve like A will represent the relation between X-ray intensity and output light from screen 8 in an image tube where the thickness of the photoconductive layer 6

is zero; i. e. in an image tube of the prior art containing no layer 6. Curve B will represent a tube having layer 6 of a material which falls rapidly in resistivity as X-ray intensity rises from C to D, but less rapidly at X-ray intensities above D, and in which the resistance through the layer 6 is a rather substantial part of the resistance in the complete path of the image current. If the layer 6 were thinner so that its resistance was smaller relative to that of the rest of the complete current path mentioned above, the portion of the curve between abscissas C and D would rise less abruptly but this most abrupt rise would still occur between X-ray intensities C and D. If layer 6 comprised a different photoconductive material a curve like E having an abrupt rise between a different set of X-ray intensities F to G might be obtained. A still different photoconductor in layer 6 might give a curve like K with a fairly uniform slope over the entire range C to G.

It will be noted that the contrast between parts of the X-ray image of different intensity is proportional to the ordinate ratio at two points corresponding to the respective intensities on the characteristic curve of the Fig. 3 type. Hence, in ranges like C-D where the slope is relatively great high contrasts exist in the image on output screen 8, but lower contrasts in ranges of X-ray intensities above D and below C. Thus also the contrast over the optimum range C-D is much greater on curve B than on curve A representing an image tube not embodying my invention.

While I have described the light-image projected through the photoconductive layer as generated by a fluorescent material, my invention is also usable in a screen in which the fluorescent layer is omitted and a light image is projected in any way to traverse both the photoconductive and the photoelectrically emissive layers.

I claim as my invention:

1. An image screen for receiving a radiation image comprising a support member sandwiched between a fluorescent layer and a conductive layer, said support member and said conductive layer transparent to radiations emitted from said fluorescent layer, said fluorescent layer responsive to said radiation image, a layer of photoconductive material adjacent said conductive layer and a photoelectrically-emissive layer provided on said photoconductive layer, said photoconductive layer transmissive to a substantial portion of the radiation emitted by said fluorescent layer to allow radiation from said fluorescent layer to excite said photoelectrically-emissive layer.

2. An image screen comprising a thin support member sandwiched between a fluorescent layer and a conductive layer, said support member and said conductive layer being substantially transparent to radiations from said fluorescent layer, a photoconductive layer of a material selected from the group consisting of selenium, arsenic trisulphide and antimony trisulphide adjacent said conductive layer and a photoelectrically-emissive layer on said photoconductive layer, said photoconductive layer transmissive to a substantial portion of the radiations emitted from said fluorescent layer to allow radiations from said fluorescent layer to excite said photoelectrically-emissive layer.

3. An image screen comprising a thin support member sandwiched between a layer of zinc sulphide and a conductive layer, said support member and said conductive layer transparent to radiations from said zinc sulphide layer, a photoconductive layer of a material selected from the group consisting of selenium, arsenic trisulphide and antimony trisulphide adjacent said conductive layer and a photoelectrically-emissive layer on said photoconductive layer, said photoconductive layer transmissive to a substantial portion of radiations from said zinc sulphide layer to provide excitation of said photoelectrically-emissive layer from radiations of said zinc sulphide layer.

4. An X-ray image intensifier comprising a vacuum-tight container having an output screen comprising an electron phosphor, an input screen comprising a thin support member sandwiched between a fluorescent layer and an electrically conductive layer, said support member and said conductive member being substantially transparent to radiations from said fluorescent layer, a layer of photoconductive material adjacent said conductive layer, a photoelectrically-emissive layer on said photoconductive layer said photoconductive material transmissive to a substantial portion of the radiations emitted from said fluorescent layer and of a resistance selected to modify the response of said intensifier per unit change in X-ray intensity and an electron lens system for focusing electrons emitted by said photoelectrically-emissive layer on said output screen.

5. An X-ray image intensifier comprising a vacuum-tight container having an output screen comprising an electron phosphor, an input screen comprising a thin support member sandwiched between a fluorescent layer and a transparent conductive layer, a photoconductive layer of a material selected from the group consisting of selenium, arsenic trisulphide and antimony trisulphide adjacent said conductive layer, a photoelectrically emissive layer on said photoconductive layer, said photoconductive layer transmissive to a substantial portion of the radiation emitted from said fluorescent layer to permit excitation of said photoelectrically-emissive layer by radiations from said fluorescent layer and an electron lens system for focusing electrons emitted by said photoelectrically-emissive layer on said output screen.

6. An X-ray image intensifier comprising a vacuum-tight container having an output screen comprising an electron phosphor, an input screen onto which the X-ray image is directed comprising a support member sandwiched between a layer of zinc sulphide and transparent conductive layer, a photoconductive layer of a material selected from a group consisting of selenium, arsenic trisulphide and antimony trisulphide adjacent said electrically conductive layer, said support member, conductive layer and photoconductive layer substantially transmissive to radiations emitted from said zinc sulphide layer when irradiated by X-rays, a photoelectrically-emissive layer on said photoconductive layer responsive to radiations from said fluorescent layer and an electron lens system for focusing electrons emitted by said photoelectrically-emissive layer on said output screen.

7. A screen member for detecting radiations of the given wave length comprising a layer of photoconductive material sandwiched between a layer of electrically conductive material and a layer of photoelectrically-emissive material, said photoconductive layer and said conductive material being transmissive to a substantial portion of said radiations to be detected by said photoelectrically-emissive layer.

8. An image tube for detecting radiations of the given wave length comprising an output screen, an input screen comprised of a layer of photoconductive materials sandwiched between a layer of electrically conductive material and a layer of photoelectrically-emissive material, said photoconductive layer and said conductive layer transmissive to a substantial portion of said radiations and the resistivity of said photoconductive materials selected to modify the response of said input screen per unit change in radiation intensity in a selective wave length region.
